CLAIM

The ornamental design for a light-emitting diode wall lamp, as shown and described.

DESCRIPTION

FIG. 1 is a front view of a light-emitting diode wall lamp according to the present application;

FIG. 2 is a rear view of the light-emitting diode wall lamp according to the present application;

FIG. 3 is a left view of the light-emitting diode wall lamp according to the present application;

FIG. 4 is a right view of the light-emitting diode wall lamp according to the present application;

FIG. 5 is a top view of the light-emitting diode wall lamp according to the present application;

FIG. 6 is a bottom view of the light-emitting diode wall lamp according to the present application; and,

FIG. 7 is a perspective view of the light-emitting diode wall lamp according to the present application.

The broken lines in the drawings depict portions of the light-emitting diode wall lamp that form no part of the claimed design.
